 Goldstein & Fox P.L.L.C.(57) **CLAIM**

The ornamental design for a fabric, as shown and described.

DESCRIPTION

FIG. 1 is a top plan view of a fabric showing the claimed design;

FIG. 2 is a left side elevational view of partial area 2 within the fabric of FIG. 1; and,

FIG. 3 is a front elevational view of partial area 3 within the fabric of FIG. 1.

The dot-dash broken lines in the figures depict boundaries of the claim and form no part thereof. The evenly spaced broken line arrows labeled 2 and 3 in FIG. 1 identify the interior boundaries of the partial view areas. The broken line arrows and reference numerals form no part of the claimed design.
